UNITED STATES PATENT OFFICE.

THOMAS PILKINGTON, OF SAN FRANCISCO, CALIFORNIA.

AMALGAMATING APPARATUS FOR EXTRACTING GOLD.

SPECIFICATION forming part of Letters Patent No. 546,079, dated September 10, 1895.

Application filed December 20, 1894. Serial No. 532,476. (No model.)

To all whom it may concern:

Be it known that I, THOMAS PILKINGTON, a citizen of the United States, residing in the city and county of San Francisco, State of California, have invented certain new and useful Improvements in Amalgamating Apparatus for Extracting Gold; and I hereby declare the following specification and the drawings therewith to be a complete description of my invention and the method of applying the same in practice.

My improvements relate to what is called "plate amalgamation," wherein the pulp or pulverized ore and quicksilver therewith are brought into maintained contact with silvered surfaces, to which the gold and quicksilver, or amalgam, will adhere by the affinity of the metals.

My improvements consist in disposing the silvered surfaces in the form of a revoluble open-ended cylinder that can be set immediately in front of a stamp battery, lined on its interior with silvered plates, and provided with baffling or agitating vanes that keep the pulp continuously in contact with the plates, and in devices to operate and otherwise apply the invention, as hereinafter pointed out and explained.

The objects of my invention are to provide a large amount of plate surface in a small space near the crushing machinery; to thoroughly diffuse and flow the pulp over the plates, repeatedly if required; to have the plates easily accessible and in view at all times, and to provide for the easy interchange of plates by substituting the revoluble cylinders, so that one can be cleaned when another is in use.

I am aware that rotary amalgamating-machines of many kinds have been made and used for the extraction of gold, and that such rotary machines have been provided with cylinders lined with silver-plated surfaces; but such machines, so far as I am aware, have not embodied operating advantages or permitted ready handling, cleaning, and other conveniences required in gold-milling processes, and it is to these objects my invention is especially directed, as will now be explained in connection with the drawings, in which—

Figure 1 is a transverse section through an amalgamating-cylinder constructed accord-

ing to my invention, taken on the line *xx*, Fig. 2. Fig. 2 is a longitudinal section on the axis of the same cylinder, taken on the line *yy* of Fig. 1. Fig. 3 is a detail showing the method of mounting and holding the baffling or diffusing vanes in the cylinder.

Similar letters of reference indicate corresponding parts.

The main cylinder consists of the heads *A'* and *A²* and a barrel *B*, made preferably of wooden staves fitting within circular ledges or flanges *C*, the whole being clamped together by through-bolts *D*, as seen in Fig. 2. At the ends of the barrel *B* are placed elastic packing-rings *E*, so as to form water-tight joints in the corners of the cylinder.

On the head *A'* is formed a circular spout *G*, from which the waste material can be discharged into a trough *F*, to be from there conveyed to a wasteway or a receptacle for further treatment.

Pulp, or ore and water is fed to the cylinder through a spout *H*, or in any other suitable manner through the head *A²*, the opening in which is made smaller than the diameter of the circular discharge-spouts *G*, as shown in Fig. 2.

Around the interior of the barrel *B* is placed a plate or lining *I*, preferably of sheet copper, the surface of which is polished and prepared by silvering to attract and retain particles of gold or amalgam that are separated from the pulp *J* being treated.

Parallel to the axis of the cylinder and diagonal to its radius are fixed a series of vanes or flat plates *L*, that fit at their ends into seats formed by shallow ledges *M* on the interior of the heads *A'* *A²*, as shown in Figs. 1 and 3. These vanes *L* are held by cams *N*, operated by stems *O*, that project through the heads *A'* *A²* to receive the handles *P*, as shown in Fig. 3. The forward or impelling sides of these plates *L* are also polished and silvered to catch fine gold that comes in contact therewith and is not deposited on the outer or main plate *I*.

The cylinder *I* mount on rollers *Q* *Q*, having grooves in which the rims of the ends *A'* *A²* fit, as seen in Fig. 2, leaving the cylinder free to be removed or rolled off and substituted with another one when its amalgamating surfaces are sufficiently charged.

The rollers Q are mounted on shafts R provided with suitable bearings, the ends projecting at S to be connected in any suitable manner to the driving power.

5 The operation is as follows: The cylinder is set in slow rotation, by means of the shafts R and rollers Q, in the direction indicated by the arrow in Fig. 1. Pulp is then run in through the spout H and assumes approximately the 10 form shown at J, Fig. 1, the vanes L directing the pulp outward and causing it to rise, impinge, and be diffused over the surface of the plate I or over the interior of the cylinder, the forward surfaces of the plates L also being exposed to and washed by the pulp J, which slowly makes its way to the other end of the cylinder and is discharged over the spout G. When the interior I of the cylinder and the forward faces of the vanes L are sufficiently charged, or at the end of a predetermined time, the flow of pulp in the spout H is shut off, and the cylinder is rolled out of its seat and replaced by another one that has been cleaned, or the collected gold and amalgam removed therefrom. The plates L are then removed, their surfaces and also the main plate I are scraped or cleaned, and the cylinder is again ready to be rolled into place, as before. In this manner it will be seen that the 20 amalgamating surfaces or plates, collectively, can be set close to the pulverizing machinery, have a large effective area within a small space, and be seen and inspected as the process goes on; also, that the cylinders and plate-surfaces can be almost instantly removed without detention for cleaning, renewal, or substitution.

Having thus described the nature and object of my invention, what I claim as new, and desire to secure by Letters Patent, is—

1. In gold-extracting apparatus, a rotary open-ended amalgamating cylinder, in the manner described, its interior lined with plates and provided with a series of removable vanes, set diagonally to the face of the plates and at some distance therefrom, the main cylinder open at its ends to permit access and observation while the process is go-

ing on, in the manner substantially as described.

2. In gold-extracting apparatus, a rotary amalgamating cylinder lined with and containing plates for the deposit of amalgam or gold, its ends formed of annular rings or plates, and its barrel of staves held by through bolts, so the whole can be separated or assembled to facilitate cleaning or repairing, and the removable vanes or plates set diagonally to the face of the lining plates and away therefrom, in the manner substantially as de- 60 scribed.

3. In gold-extracting apparatus, a revolvable amalgamating cylinder lined on its interior side with a continuous catch plate or plates, in the manner described; a series of removable 65 vanes or plates set parallel to the axis, and oblique to the radius of the cylinder and away from the catch plates, so as to cause the contained pulp to be directed toward the plates and to pass between these and the vanes to 70 secure impingement upon and constant action of the plates, substantially as described.

4. In gold-extracting apparatus, a revolvable amalgamating cylinder mounted on and impelled by friction rollers, in the manner de- 75 scribed, its interior lined with a plate or plates, and a series of parallel plates fixed therein, the latter held by cams, and removable by means of handles on the outside of the cylinder, substantially as described.

5. In gold-extracting apparatus, a revolvable amalgamating cylinder mounted and revolved by rollers, in the manner described; annular ends held by through bolts, and one end formed with a discharge nozzle or spout; a 85 series of removable baffling or diffusing plates set clear of the plates and held by an adjusting device operated from the exterior of the cylinder, substantially as described.

In testimony whereof I have hereunto affixed my signature in the presence of two witnesses.

THOMAS PILKINGTON.
